(57) **CLAIM**

The ornamental design for a connector, as shown and described.

DESCRIPTION

FIG. 1 is a front, top, and side perspective view of a connector.

FIG. 2 is a back, top, and side perspective view thereof.

FIG. 3 is a top view thereof, the bottom being a mirror image.

FIG. 4 is a side view thereof, the opposite side being a mirror image.

FIG. 5 is a front view thereof; and,
FIG. 6 is a back view thereof.

The portions of the connector adaptor shown in broken line form no part of the claimed design.

The evenly spaced broken lines in the drawings illustrate portions of the connector and form no part of the claimed design. The dot-dash-dot broken lines in the drawings define the bounds of the claim and form no part thereof.
